UNITED STATES PATENT OFFICE.

ALBERT REED, OF OROVILLE, CALIFORNIA.

IMPROVEMENT IN MACHINES FOR TRANSMITTING POWER.

Specification forming part of Letters Patent No. **155,674**, dated October 6, 1874; application filed August 29, 1874.

To all whom it may concern:

Be it known that I, ALBERT REED, of Oroville, in the county of Butte and State of California, have invented a new and Improved Machine for Transmitting Power, of which the following is a specification:

In the accompanying drawing, Figure 1 represents a vertical longitudinal section of my improved machine for transmitting power; Fig. 2, an end view, and Fig. 3 a vertical transverse section, of the same on the line *c c*, Fig. 1.

Similar letters of reference indicate corresponding parts.

The object of my invention is to facilitate the transmission of power for the purpose of working pumps, sawing-machines, &c.; and the invention consists of suitable weighted, swinging, and regulating devices, which produce, when set to work, a uniform degree of motive power.

In the drawing, A and A' represent strong front and rear frames for supporting the various operating devices. The front frame, A, is provided with a centrally-pivoted lateral frame, B, being operated by means of a weighted lever-arm, B¹, and handle B². The upward-extending part of frame B supports a pivoted elbow-lever, C, to which is attached, at the outermost end, a weight, C', which increases the momentum of lever C, and transmits motion, by a link, D, to a centrally-fulcrumed lever, E. The opposite end of lever E connects with a vertically-swinging arm, F, which is fulcrumed to the rear frame A', and connected rigidly, under right angles, with a top piece, F¹, having friction-rollers F² at

their outer ends. The friction-rollers F² support a pivoted carriage, G², with concaved top part, which connects, by a downward-extending rigid arm, G¹, with the lower end of a fulcrumed arm, G², that is hung with its upper end to a horizontally-swinging top lever, H. The top lever H has a weight, H¹, at the rear end, and is supported on the concaved top of pivoted carriage G by a readily-turning friction-roller, H², which increases, in connection with the swinging motion of the carriage, the power of the strokes of top lever H. The fulcrum of top lever H is secured on the upper part of the front frame A, the forward end of lever H being attached to cords L, which pass over suitable side and top pulleys of frame A to the ends of a centrally-pivoted lateral lever, M, to which the pump or other machinery to be driven is attached.

By setting the operating-handle in motion, the various parts are consecutively brought into active operation, until the final reciprocating motion of lever M is obtained.

Having thus described my invention, I claim as new and desire to secure by Letters Patent—

The combination of pivoted weighted levers B B¹, pivoted weighted elbow-levers C C', levers E and F, swinging carriage G G¹, laterally-swinging top lever H, and cords L with reciprocating front lever M, substantially in the manner and for the purpose set forth.

ALBERT REED.
